UNITED STATES PATENT OFFICE.

CARL MOLSTAD, OF NEWFOLDEN, MINNESOTA.

CLEANER FOR SKIMMING DISKS OF CREAM SEPARATORS.

Application filed July 1, 1927. Serial No. 202,898.

My invention relates to cleaning devices for the skimming disks of cream separators and has for its principal object to provide a container for rotatably mounting the disks in nested relation and interposing a cleaning element in a fixed position to the container and extending between each of the disks and adapted to engage both the upper and lower faces thereof so that both sides of the disk will be simultaneously cleaned as the same are rotated.

Another object is to provide means extending from the container for rotating the disks during the cleaning operation.

A still further object is to provide means for easily and quickly mounting the disks in cleaning position within the container and permitting the removal therefrom in the same relative position for attaching to a drying frame.

A still further object is to provide means for detachably securing the cleaning element to the casing or container in order that the same may be readily and quickly replaced when the same becomes worn out through usage.

Other objects and advantages reside in the special construction, combination and arrangement of the various elements forming the invention as more fully hereinafter described and claimed, reference being had to the accompanying drawings forming part hereof, wherein:

Figure 1 is a side elevational view showing my skimmer disk cleaner in operative position,

Figure 2 is a fragmentary vertical sectional view showing the manner in which the cleaning element engages the opposite faces of the disk,

Figure 3 is a perspective view of the cleaner supporting arm,

Figure 4 is a detail showing the support for attaching the cleaner arm, and,

Figure 5 is a perspective view of the hanger for drying the disks.

Referring now to the drawings I have shown my invention comprising a cleaning apparatus for skimmer disks of cream separators comprising a disk supporting frame indicated at 5 including vertically arranged members and a pair of upper and lower transverse members indicated respectively at 6 and 7 and between which members a shaft 8 is rotatably journaled. The shaft 8 is formed in section, the upper end of which indicated

at 9 extends outwardly from the upper transverse member 6 and having a beveled gear 10 mounted at its upper end engaging a similar gear 11 arranged on a horizontal crank shaft 12 and adapted for operation by a crank arm 13. The upper and lower sections of the shaft 8 and 9 are detachably connected by a sleeve 14 which may be provided with a square-shaped bore for receiving the squared adjacent ends of the sections of the shaft to insure the simultaneous rotation thereof. A coil spring 15 is mounted on the upper section 9 interposed between the sleeve 14 and the upper transverse member 6 whereby to maintain the sleeve in connected position. The sections of the shaft may be disconnected by forcing the sleeve 14 upwardly against the pressure of the spring whereby the lower section 8 is adapted to be removed from the frame.

A plurality of cream separator skimmer disks indicated at 16 are adapted to be carried on the lower shaft section 8 in nested relation with each other, said disks being usually provided with a central opening having slots formed at opposite sides thereof for receiving ribs 17 longitudinally arranged on the shaft to insure the rotation therewith.

One of the vertical frame members as shown at 18 may be hingedly connected at 19 near its lower end permitting the same to be swung outwardly away from the frame so that the shaft 8 together with the disks 16 may be readily removed from the frame. The upper end of the hinged member 18 may be releasably connected to the frame by means of a slidably disposed ring 20.

Openings 21 extend transversely through the hinged member 18 and are arranged in a double vertically extending row near each end of the member 18, said openings being adapted to receive the outer ends 22 of cleaner rods 23. The cleaner arm 23 is composed of a pair of parallel rods having their inner ends connected as at 24, the opposite ends 22 being free for insertion in openings 21. The ends 22 of the arms are turned outwardly to extend in opposite directions as shown in Figure 3 of the drawing whereby to normally prevent inward movement of the arms and a pair of similarly formed lugs 22' are formed slightly inwardly from the end 22 for engaging the opposite face of the hinged member 18 whereby to normally prevent the outward movement of the arms. The arms preferably should be constructed of spring steel to ren-

der the same substantially rigid but at the same time permitting the free ends of the arm to be moved slightly together whereby to permit the same to be removed from the openings 21. The inwardly extending ends of the arm are provided with a pair of inturned projections indicated at 25 forming a guide for a strip of cloth indicated at 26 adapted to be secured to the hinged member 18 by clips 27 and threaded through rings 28 arranged on the inner face of the hinged member so that the cloth may be extended in continuous formation longitudinally along the upper and lower sides of the arm and through the guides 15 formed by the projections 25. The arms are arranged to extend between the upper and lower faces of the adjacent skimmer disks so that the cloth 26 will engage the faces thereof, it being obvious that upon the rotation of 20 said disks that both faces of the same will be thoroughly cleaned by contact with the cloth 26.

During the cleaning operation the entire frame 5 carrying the skimmer disks may be 25 immersed in a container carrying a suitable cleaning fluid. After the disks have been thoroughly cleaned the same may be removed from the frame and arranged on a drying rack shown in Figure 5 of the drawing, said 30 rack including a bar 30 coinciding with the shaft 8 and having a wire handle 29 engaging the opposite ends thereof by means of which the rack may be suitably suspended during the drying of the disks.

It is believed the manner of operation of 35 the device will be thoroughly understood from the foregoing description as well as the advantages derived through the use thereof. The provision made for replacing the cleaning cloth 26 is of particular advantage inasmuch as this cloth must be replaced from time to time as the same becomes worn through usage.

It is obvious that the invention is susceptible 40 to various changes and modifications without departing from the spirit thereof or the scope of the appended claims and I accordingly claim all such forms of the device to which I am entitled.

I claim:

1. In an apparatus of the class described, a 45 rotatably mounted shaft adapted to carry a plurality of skimmer disks, means connected with said shaft for the operation thereof, and a plurality of cleaner arms extending 55 between said disks and arranged in cleaning position with the surfaces thereof.

2. In a device of the class described, a frame 60 having a shaft rotatably arranged therein and adapted to support a plurality of skimmer disks in nested relation, operating means for said shaft carried by the frame, and a plurality of cleaner arms interposed between said

disks and engaging the adjacent surfaces thereof.

3. A skimmer disk cleaner comprising a frame having a shaft rotatably mounted therein, means carried by the frame for operating said shaft, said shaft being adapted to carry a plurality of skimmer disks in nested 70 relation and a plurality of arms removably secured by one end to the frame with the opposite end of each thereof extending inwardly between the faces of the various disks, each of said arms being adapted to engage the 75 upper face of one of said disks and the lower face of an adjacent disk.

4. In a skimmer disk cleaner a frame having a sectional shaft rotatably carried therein, one section of said shaft being adapted to 80 carry a plurality of skimmer disks in nested relation, and detachably connected with the remaining section of said shaft permitting the removal of the disk carrying section from the container, means carried by the container 85 for operating said shaft, a hingedly connected member arranged at one side of the frame, a plurality of cleaner arms removably connected at one end to said hinge member with their opposite ends extending inwardly of the 90 frame and arranged between each of the disks, said arm carrying a strip of continuously 95 formed cleaning material secured at opposite ends to the hinged member and arranged longitudinally along the upper and lower sides of the arms and adapted to engage the opposite faces of adjacent disks.

5. In a disk cleaner, a rotatable disk supporting shaft, and a fixedly mounted cleaning arm having a cleaning element attached 100 thereto extending between the disks on said shaft in cleaning engagement with the adjacent faces thereof.

6. In a disk cleaner, a rotatable disk supporting shaft and a plurality of stationary 105 cleaner arms forming cleaning faces for the disks on said shaft and provided with a cleaner element on their upper and lower sides in cleaning relation with the adjacent faces of the disks.

7. In a disk cleaner comprising a frame having a hinged section at one side, a removable disk supporting shaft rotatably mounted within the frame, a plurality of stationary 115 cleaner arms, each arm being attached at one end to said hinge section with its free end extending radially between a pair of the disks on said shaft, spaced guide means formed at the free end of the arm and spaced retaining means carried by said hinged section adapted 120 to support a cleaner face in longitudinally extended position upon the opposite sides of the arm in cleaning relation with the opposed surfaces of said disk.

In testimony whereof I affix my signature.
CARL MOLSTAD.
